UNITED STATES PATENT OFFICE.

CHARLES CALVERT LAMB, OF CHICAGO, ILLINOIS.

WASHING MACHINE.

1,403,966.

Specification of Letters Patent. Patented Jan. 17, 1922.

Application filed October 25, 1920. Serial No. 419,397.

To all whom it may concern:

Be it known that I, CHARLES C. LAMB, a citizen of the United States, residing at Chicago, in the county of Cook and State of Illinois, have invented new and useful Improvements in Washing Machines, of which the following is a specification.

This invention relates to washing machines and more particularly to gearing 10 therefor.

Among the objects of my invention is to provide an improved form of gearing with clutches, so that a perforated or foraminated clothes container may be rotated at a slow 15 rate of speed for washing and a greater rate of speed for centrifugal wringing, the arrangement being such that the container may be rotated for wringing by throwing the same into clutch with the high speed 20 gear train without lifting the container from washing position and without at any time stopping the rotation of the container.

In the accompanying drawings—

Fig. 1 is a side elevational view, with 25 parts in section, of a washing machine constructed in accordance with my invention;

Fig. 2 is an end view of the machine;

Fig. 3 is a top plan view thereof;

Fig. 4 is a view looking down into the 30 gear box, the cover thereof being removed for that purpose;

Fig. 5 is a vertical sectional view taken through the gear box on the indirect line 5-5 of Fig. 4;

Fig. 6 is a fragmentary vertical sectional view taken on line 6-6 of Fig. 1; and

Figs. 7 and 8 are views of details of construction to be hereinafter described.

The washing machine of my invention, as 40 shown in the drawings, has a supporting base or stand 1, made of upper and lower rectangular open frames 2, 3, connected at the four corners by angle-bars 4. The stand has casters or rollers 5 so that the machine 45 may be rolled over the floor.

Located within and between the top and bottom frames 2, 3 is a gear box 6, substantially centrally arranged and supported by the lower frame 3 on cross-bars 7, 7, as 50 shown in Figs. 3 and 4. The box 6 has a lid 8, through which extends a vertically arranged main operating or driven shaft 9. Loose on this shaft inside of the box is a worm gear 10 in mesh with a worm 11 also 55 in the box and fixed on a horizontally ar-

ranged shaft 12 secured by a coupling 13 to the armature shaft 14 of an electric motor 15 mounted on the lower frame 3 exterior of the box, at one side thereof, as shown in the drawings. Said shaft 9, as shown in Fig. 5, extends to and is stepped in the bottom wall 16 of the box, and fixed to said shaft adjacent its lower end are two collars 17, 17, between which are bearing balls, as shown. The lower collar is retained in an annular recess provided in the bottom wall of the box to provide a side thrust bearing for the lower end of said shaft. The lid 8 has a depending boss 18 on its under side to receive collars with bearing balls between them to provide a side thrust bearing for the shaft 9 in the lid, as shown in said Fig. 5. The shaft 9 also extends through a bridge plate 19 in the box, extending between and secured to the side walls thereof. The worm gear 10 is supported by this plate and has its hub seated in a boss 20 projecting upward from the plate.

Splined on the shaft 9 between the lid 8 and the worm gear 10 is a clutch sleeve 21 having clutch teeth 22 to engage notches 23 in the worm gear 10, so that the worm gear 10 may be connected to and disconnected from the shaft 9. The sleeve 21 is moved vertically into and out of clutch with the worm gear 10 by a rock shaft 24 extending into the gear box 6 through one side thereof, as shown in Fig. 4. Any suitable form of connection may be employed between the rod and sleeve for raising and lowering the same, but, as shown in Figs. 4 and 8, such connection comprises an endwise slidable bar 25 in the annular groove of the sleeve, engaged by a pin 26 fixed to a disc 27 secured to the inner end of the rock shaft 24. When the shaft 24 is turned, the pin is carried with the disc and raises and lowers the sleeve, the bar sliding in the groove, as is apparent.

On the stand 1 is a tub 28 cylindric in shape, with its upper end open and its bottom wall 29 resting on the upper frame 2. The tub is removably connected with the frame by providing the tub at its bottom with a plurality of outwardly projecting apertured lugs or ears 30 to receive upright pins 31 carried by and projecting above the top frame 2. In the center of the tub is an upright tube 32, which extends downward through the bottom wall of said tub and is

- secured thereto by bosses 33, 33, as shown in Fig. 7. This tube is open at both ends and fits over the portion of the shaft 9 which extends above the gear box. The tube 32 is stationary as the tub is held against rotation by its weight and the pins and lugs mentioned. The shaft 9, as shown in Fig. 6, extends above the upper end of the tube 32 and has its upper end squared, as at 34.
- 10 Located in the tub 28 is a perforated or foraminated annular container or basket 35 provided on the inside with an upright tube 36 rigidly secured and opening downward through the bottom wall of the basket, so 15 that the basket tube may fit over the one secured to the tub. The tube 36 extends above the top of the basket and there has an annular block or cap 37 secured to it. This block rests on a shoulder provided on 20 the shaft 9 by the squared upper end thereof. The block 37 has a like shaped hole to receive the squared upper end of the shaft 9 to connect the basket and shaft together, so that the shaft when rotated will 25 turn the basket. Vertical displacement of the basket is prevented by a headed screw 38, as shown in Fig. 6.
- The machine includes two vacuum cups or 30 pounders 39, 39 reciprocated up and down in the basket during the washing operation and while the basket is rotated by the shaft 9. To support the pounders, I provide a cross-bar or plate 40, which extends across the top of the tub and rests on the upper 35 edge thereof, as shown in Figs. 1 and 2. Depending from the under side of the bar 40 are two brackets 41, 41, one for each pounder. Each pounder is secured to the lower end of a vertical rod 42, its upper 40 end extending into its associated bracket 41 and secured to a cross-head 43, which has a sliding connection with the side members of the bracket. Above the plate 40 is a horizontally arranged shaft 44 having its ends 45 journaled in upright standards 45, 45 on said plate. At each end of the shaft there is a crank arm 46 connected by a pitman 47 with the associated cross-head 43. Fixed 50 on the shaft 44 is a beveled gear 48 in mesh with a beveled gear 49 fixed to the upper end of a tubular shaft 50 extending through and above the plate 40. This shaft is supported on the plate by the hub of the gear 49 resting on a collar 51. Secured to the 55 lower end of the shaft 50 is a member 52 having a plurality of teeth 53 to engage in notches or recesses 54 in the end cap 37 on the tube 36, as shown in Figs. 1 and 6. This allows the shafts 9 and 50 to be readily and 60 easily disconnected by merely lifting up the plate 40 when the pounders are to be removed from the machine, as when the basket 35 is to be run at a rapid rate of speed for centrifugal wringing. This type of connection between the shafts 9 and 50 also al-

lows the same to be readily coupled together when the pounders are placed back in the machine for washing.

To hold the plate 40 in proper position on the tub, I provide a plurality of downwardly extending fixed pins 55, 55 at each end of the plate to engage over the inside and outside of the upper edge of the tub 28, as shown in Figs. 1 and 3. These pins when engaging the tub prevent endwise displacement of the plate, and to hold the plate against moving circumferentially about the tub, I provide upwardly projecting lugs 56, 56 on the tub on opposite sides of the plate at each end thereof. To hold the plate 40 against the tub, I provide at each end of the plate a resilient latch member 57 secured to the outside of the tub below the adjacent end of the plate and adapted to engage over or in a notch in the plate. 85

So much of the construction described operates as follows. Operating the motor 15 rotates the worm gear 10 and, when the sleeve 21 is moved into clutch with the worm gear, the shaft 9 is rotated and turns the 90 basket 35 at the rate of speed provided by the worm gear 10. The shaft 50 is driven by the shaft 9 and the pounders 39 are reciprocated up and down as the basket 35 is revolved. These parts are continued in 95 operation until the washing operation has been completed. The motor is then disconnected from the shaft 9 by raising the sleeve 21 out of clutch with the gear wheel 10. To facilitate turning of the rock shaft 100 24, I provide an operating lever 58 located at one side of the tub 28 and having a length to extend to a point above the tub and there having a handle to facilitate ready grasping and operating of the lever. The lower end 105 of the lever is fixed to the outer end of the rock shaft 24, as shown. Co-operating with the lever 58 is a plate 59 secured to the tub 28 on the outside thereof. This plate has a notch intermediate its ends to receive a 110 latch 60 carried by the lever 58 and to hold the lever in substantially upright or neutral position. In such position, the clutch sleeve 21 is out of engagement with the worm gear 10 so that no power can be imparted to the 115 shaft 9, should the motor be started. When the lever is moved to either side of the neutral position, it is slightly out of vertical, and the weight of the lever holds it in that position. When the lever is at the left of its 120 neutral position, as shown in dotted lines in Fig. 2, the sleeve 21 is in clutched engagement with the gear wheel 10 and the basket 35 and pounders 39 operated for washing.

To wring the clothing in the basket 35 by 125 centrifugal force, I provide means for rotating the basket at the high rate of speed required for that purpose. Such means comprises a gear train as follows. In the gear box 6 is a vertical shaft 63 having its 130

upper and lower ends journaled in the lid 8 and bottom wall 16 of the box, respectively, similar to the main shaft 9. This shaft 63 also extends through the bridge 5 plate 19, and loose on the shaft above the bridge plate is a worm pinion 64 in mesh with a worm 65 on the shaft 12. Fixed to the shaft 63 below the bridge plate is a gear wheel 66 in mesh with a gear pinion 67 fixed 10 to a counter-shaft 68 extending between the bridge plate 19 and the bottom wall 16 of the box and journaled therein, as shown. Fixed on the shaft 68 below the pinion 67 is a gear wheel 69 in mesh with a gear pinion 70 fixed on the main shaft 9. Splined on the shaft 63 above the worm pinion 64 is a clutch sleeve 71 having an annular groove engaged by a shifter yoke 72. This yoke is at the inner end of a lever 73 pivoted at 74 15 between lugs 75 on the outside of the gear case 6, as shown in Figs. 4 and 5. The lever 73 extends outward beyond that side of the machine where the shift lever 58 is located, and said lever 58 is provided at its lower 20 end with a fork 76 to engage the outer end of the pivoted lever 73, as shown in Figs. 1 and 2. The worm pinion 64 and clutch sleeve 71 have coacting parts for clutching the two together when the sleeve 71 is 25 moved into engagement with the worm pinion, so that the worm pinion may be connected with the shaft 63 when it is desired to rotate the basket 35 for wringing purposes. In the form shown in the drawings, 30 this clutch construction is of the friction type and comprises a cone clutch, one part 77 of which is on the sleeve 71 and the other part 78 on the worm pinion 64.

The parts thus described operate as follows. After the clothing in the basket 35 35 has been washed by rotating the basket at a slow rate of speed, the faucet 79 is opened to drain the dirty water out of the tub 28.

The basket and pounders are allowed to 40 continue to operate while the dirty water is being drained. After the tub is sufficiently drained, the faucet is closed and clean boiling or hot water is run into the tub, the basket and pounders still kept in operation to effect a thorough rinsing of the clothes. The faucet is again opened and the rinsing 45 water let out, thereupon the lever 56 is moved into neutral position, as shown in full lines in Figs. 1, 2 and 3. This rocks the shaft 24 and raises the sleeve 21 out of clutched engagement with the worm gear 10 to disconnect the basket and the pounders from the motor 15. Then the pounders are 50 removed from the tub by lifting the cross-plate 40 off of and clear of the tub. This lifts the stop lug or part 80 on the end of the cross-plate 40 out of the path of the lever 58, and permits said lever to be thrown 55 into wringing position. The lever 58 is 60 then moved from neutral position to wring-

ing position, as shown in dotted lines at the right in Fig. 2. This action causes the lever 58 to raise the outer end of the lever 73 and throws the inner end down, carrying therewith the sleeve 71 and moving the same into 70 frictional clutched engagement with the worm pinion 64, the motor of course being in operation. This connects the basket 35 with the shaft 9 through the gear train between the shaft 9 and the shafts 63 and 68, 75 to rotate the basket 35 at that high rate of speed required to throw the water out of the clothing by centrifugal force. The gear train for both washing and wringing is so arranged and constructed that the basket 80 35, when washing as well as wringing, is rotated in the same direction, so that the basket may be started for wringing through the slow gear train and then thrown into high speed for wringing immediately, without stopping the basket, as the basket rotating under its own momentum from washing speed avoids throwing a sudden heavy load on the motor. This permits the motor to take up its load without jar and thus permits it to impart a maximum speed to the shaft 9 through the gear train described in a minimum amount of time. This is also facilitated by the clutch sleeves being operated by one lever 58, as one clutch sleeve 85 90 is thrown out before the other is thrown in, and both sleeves cannot be thrown in at the same time.

The shaft 44 and the cranks for the pounders are all housed in a casing 81 secured on top of the cross-plate 40. This casing may be rigidly secured to the plate and be provided with a removable top or cover so that the shaft 44 and the cranks and adjacent parts may be readily reached for inspection or repair and also be placed in the casing during the initial building of the machine. Providing the stop 80 on the cross-plate 40 prevents the clutch sleeve 71 from being moved into clutch with the gear pinion 64 while the pounders are in the machine, thus preventing the machine from being thrown into wringing operation until the pounders are removed.

Arranging and locating all of the members of the gear train, including the clutches for the washing and wringing operations, in a gear box, which is closed by a top plate 8, permits packing the box with grease at the initial building of the machine so that 115 all of such parts will be maintained well and fully lubricated and thus avoids the necessity of lubricating the parts of the machine after originally built and assembled. This is a great advantage in washing machines which are designed for domestic use, as the users are not usually familiar with mechanical parts and, more than likely, prone to omit oiling of the parts due to lack 120 of knowledge and also lack of facilities. 130

While I have shown and described herein in detail a washing machine embodying the features of my invention, it is of course to be understood that the various details of construction and arrangement of parts may be variously changed and modified without departing from the spirit and scope of my invention.

I claim as my invention:

- 10 1. In combination in a gearing of the character described, a supporting stand, a gear box on said stand, a main driven shaft and a counter-shaft, both journaled in said box with the main shaft extending outward therefrom, a motor on said stand outside of said box and having its armature shaft extending into the same, a slow speed gear train and a high speed gear train, the latter including said counter-shaft, both gear trains being located in said box and each providing a separate power transmitting connection between the armature shaft and said main shaft, a single clutch means in each gear train, the clutch means for one gear train being mounted entirely on one of said shafts, and the clutch means for the other gear train being mounted entirely on the other of said shafts, a single lever outside of said gear box for actuating both clutch means for connecting the motor with the main shaft through either of said gear trains, and means connecting said lever with said clutch means in a manner causing the lever when moved out of neutral position to throw only one clutch means into clutched engagement with its associated gear train.

- 20 2. In combination in a gearing of the character described, a supporting stand, a gear box on said stand, a main driven shaft and a counter-shaft, both journaled in said box with the main shaft extending outward therefrom, a motor on said stand outside of said box and having its armature shaft extending into the same, a slow speed gear train and a high speed gear train, the latter including said counter-shaft, both gear trains being located in said box and each providing a separate power transmitting connection between the armature shaft and said main shaft, a single clutch means in each gear train, the clutch means for one gear train being mounted entirely on one of said shafts, and the clutch means for the other gear train being mounted entirely on the other of said shafts, and means operable from the outside of said gear box for actuating said clutch means for connecting the motor with the main shaft through either gear train, and constructed so that when one clutch means is in clutched engagement with its gear train the other clutch means is prevented from being moved into clutched engagement with its gear train.

- 30 3. In combination in a gearing of the character described, a supporting stand, a gear box on said stand, a main driven shaft and a counter-shaft, both journaled in said box with the main shaft extending outward therefrom, a motor on said stand outside of

said box and having its armature shaft extending into the same, a slow speed gear train and a high speed gear train, the latter including said counter-shaft, both gear trains being located in said box and each providing a separate power transmitting connection between the armature shaft and said main shaft, a single clutch means in each gear train, the clutch means for one gear train being mounted entirely on one of said shafts, and the clutch means for the other gear train being mounted entirely on the other of said shafts, a single lever outside of said gear box for actuating both clutch means for connecting the motor with the main shaft through either of said gear trains, and means connecting said lever with said clutch means in a manner causing the lever when moved out of neutral position to throw only one clutch means into clutched engagement with its associated gear train.

4. In combination in a gearing of the character described, a supporting stand, a gear box on said stand, a main driven shaft and a counter-shaft, both journaled in said box with the main shaft extending outward therefrom, a motor on said stand at one side of said box and having its armature shaft extending into the same, a slow speed gear train and a high speed gear train, the latter including said counter-shaft, both gear trains being located in said box and each providing a separate power transmitting connection between the armature shaft and said main shaft, a single clutch means in each gear train, said clutch means being of the friction cone type, the clutch means for one gear train being mounted entirely on one of said shafts, and the clutch means for the other gear train being mounted entirely on the other of said shafts, and a single lever outside of said box for actuating said clutch means for connecting the motor with said main shaft through either gear train.

5. In combination in a gearing of the character described, a main driven shaft, a second driven shaft, a worm gear loose on each of said shafts, a worm meshing with each of said worm gears, a motor for driving said worms simultaneously and in the same direction, a high speed gear train connecting the second shaft with said main shaft, a shiftable clutch member splined on each of said main and second shafts and adapted to be moved into and out of clutched engagement with the worm gear thereon, and means for shifting said clutch members.

6. In combination in a gearing of the character described, a main driven shaft, a second driven shaft, a worm gear loose on each of said shafts, a worm meshing with each of said worm gears, a motor for driving said worms simultaneously and in the same direction, a third shaft, meshing high

speed gear wheels fixed on said main, second and third shafts, a shiftable clutch member splined on each of said main and second shafts and adapted to be moved into and out 5 of clutched engagement with the worm gears thereon, and means for shifting said clutch members.

7. In combination in a gearing of the character described, a supporting stand, a 10 gear box on said stand having a cover, a main driven shaft journaled in said box and extending outward through said cover, a motor on said stand outside of said box and having its armature shaft extending 15 into the same, a slow speed gear train and a high speed gear train, both located in said box and each providing a separate power transmitting connection between the armature shaft and said main shaft for enabling 20 the motor to rotate said main shaft either at a slow or high speed and in the same direction, two shiftable clutch members in said box, one in each gear train, for connecting the armature shaft with said main shaft 25 through either gear train, a rock shaft and a pivoted lever, both extending into said box and connected, respectively, with said clutch members, and a single lever outside of said box and connected with said rock shaft and 30 said pivoted lever for moving the same simultaneously.

8. In combination in a gearing of the character described, a supporting stand, a gear box on said stand and having a cover, a main driven shaft journaled in said box and extending outward through said cover, a motor on said stand outside of said box and having its armature shaft extending into the same, a second shaft journaled in said 35 box and arranged substantially parallel to the main shaft, a worm gear loose on each of said main and second shafts, a third shaft in said box, arranged transverse to said other shafts and coupled to said armature 40 shaft, two worms fixed on said third shaft and meshing one with each of said worm gears, a high speed gear train connecting said second shaft with said main shaft, a shiftable clutch member splined on each of 45 said main and second shafts and adapted to be moved into and out of clutched engagement with the worm gear thereon, and a lever outside of said box and connected with said clutch members for shifting the 50 same.

9. In combination in a gearing of the character described, a supporting stand, a gear box on said stand and having a cover, a bridge plate fixed in said box, a main driven 55 shaft journaled in said box and extending through said bridge plate and projecting outward through said cover, a second shaft journaled in said box substantially parallel to said main shaft and extending through

said plate, a motor on said stand outside of 65 said box and having its armature shaft extending into the same, a worm gear loose on each of said main and second shafts and supported by said bridge plate, a third shaft in said box transverse to the other shafts 70 and coupled to said armature shaft, two worms fixed on said third shaft and meshing one with each worm gear, meshing high speed gear wheels in said box below said plate and connecting the main shaft to said 75 second shaft, a clutch member splined on each of said main and second shafts and adapted to be moved into and out of clutched engagement with the worm gear loose thereon, and a lever located outside of said box 80 and connected with both of said clutch members for shifting the same.

10. In a gearing of the character described, a supporting stand, a gear box on said stand, a main driven shaft journaled 85 in said box and projecting upward therefrom, a motor on said stand outside of said box and having its armature shaft extended into the same, a slow speed gear train and a high speed gear train, both located in 90 said box and providing a separate power transmitting connection between said armature shaft and said main shaft for enabling said motor to rotate said main shaft at either a slow or high speed, a shiftable clutch 95 member in each gear train for connecting the motor with said main shaft through either gear train, means outside of said box and connected with said clutch members for moving the same into and out of clutched engagement with their associated gear trains, a counter-shaft supported above said stand, vertically arranged rods between said counter-shaft and said stand, means connecting the upper ends of said rods with said counter-shaft for reciprocating said rods, and a power transmitting connection between said main shaft and said counter-shaft.

11. In a gearing of the character described, a supporting stand, a gear box on 110 said stand, a main driven shaft journaled in said box and projecting upward therefrom, a motor on said stand outside of said box and having its armature shaft extended into the same, a slow speed gear 115 train and a high speed gear train, both located in said box and providing a separate power transmitting connection between said armature shaft and said main shaft for enabling said motor to rotate said main 120 shaft at either a slow or high speed, a shiftable clutch member in each gear train for connecting the motor with said main shaft through either gear train, means outside of said box and connected with said clutch members for moving the same into and out of clutched engagement with their 125 associated gear trains, a counter-shaft sup-

ported above said stand, a vertically arranged rod between said counter-shaft and said stand, a crank arm secured to said counter-shaft and connected with the upper end 5 of said rod, a vertically arranged shaft below said counter-shaft and having detachable connection with said main shaft, and

meshing gear wheels, one on said counter-shaft and one on said vertical shaft.

In testimony that I claim the foregoing 10 as my invention, I affix my signature this 20th day of October, A. D. 1920.

CHARLES CALVERT LAMB.
